[57] CLAIM

The ornamental design for a combined fishing rod holder and bite signaller, as shown and described.

DESCRIPTION

FIG. 1 is a side elevational view of a combined fishing rod holder and bite signaller, according to my design, the opposite side (not shown) being a mirror image thereof;

FIG. 2 is a rear elevational view, the same being taken from the right-hand side of FIG. 1;

FIG. 3 is a front elevational view, the same being taken from the left-hand side of FIG. 1;

FIG. 4 is a bottom view, taken from the bottom of FIG. 1; and

FIG. 5 is a top view, taken from the top of FIG. 1.

FIG. 5

FIG. 3

FIG. 1

FIG. 2

FIG. 4
